FOOD WEIGHING SCALE

Ralph R. Dillon, Van Nuys, Calif., assignor to
Scale Data Systems, Inc.

Filed Feb. 9, 1970, Ser. No. 21,369

Term of patent 14 years

Int. Cl. D10—99

U.S. Cl. D52—10

FIG. 1

FIG. 2

FIG. 3

FIG. 4

FIG. 5

FIG. 6

FIG. 1 is a perspective view of a food weighing scale showing my new design;

FIG. 2 is a front elevational view thereof;

FIG. 3 is a side elevational view thereof showing the side not visible in FIG. 1;

FIG. 4 is a rear elevational view thereof;

FIG. 5 is a top plan view thereof; and

FIG. 6 is a bottom plan view thereof.

I claim:

The ornamental design for a food weighing scale, substantially as shown.
